ARC LAMP

Filed Sept. 25, 1946

UNITED STATES PATENT OFFICE

2,440,122

ARC LAMP

Robert E. Sheahan, Bridgeport, Conn., assignor to
 General Electric Company, a corporation of
 New York

Application September 25, 1946, Serial No. 699,287

2 Claims. (Cl. 314—40)

1

My invention relates to arc lamps, and more particularly to electrode feed control systems for such lamps.

The invention has for its principal object the provision of a new and improved apparatus for continuously feeding and simultaneously rotating an arcing electrode.

A further object of the invention is to provide, in conjunction with such apparatus, an electrode feeding and rotating mechanism which shall be of simple, light, and inexpensive construction without sacrifice of durability and dependability in operation.

In the operation of arc lamps, such as searchlights and the like, it has heretofore been common to continuously rotate but only intermittently advance the positive electrode. Purely intermittent advancement of the positive electrode may be disadvantageous in that it causes considerable fluctuation of the arc. Alternatively, it has been suggested that the positive electrode may be continuously rotated and continuously advanced at a predetermined constant speed. Such an arrangement, however, is difficult to adjust, and if not adjusted for precisely the proper rate of feed the crater will not remain in the desired position.

According to my invention the positive electrode of an arc lamp is continuously rotated and continuously advanced at one of two selectable speeds. The low speed of advancement is slightly less than and the high speed slightly greater than the normal burning rate of the electrode. In this way, the advantages of continuous forward feed and rotation are obtained, but means are also provided to ensure that the crater remains in the desired position in the event that the burning rate varies slightly.

For a more complete understanding of my invention and a further appreciation of its objects and advantages, reference should now be had to the following detailed specification, taken in conjunction with the accompanying drawing, the single figure of which is a schematic circuit diagram of an electrode feed control system for arc lamps embodying my invention, the electrode feed mechanism being shown in cross section.

Referring now to the drawing, I have shown an arc searchlight comprising a positive electrode 1 and a negative electrode 2 arranged to be connected through a contact 3 of a line contactor 4 to the corresponding terminals of a suitable source high voltage electric current supply, such as a 60-volt direct current generator 5. The line contactor 4 is provided with an actuating wind-

2

ing 6 arranged to be energized through cut-out switch 7 from a low voltage source of control power, such as a 24-volt line 8.

The negative electrode 2 is supported by a pair 5 of driving rollers 14, 15 and a pair of spring pressed electric conducting guide brushes 16, 17. Current is supplied to the electrode 2 through the brushes 16, 17, as shown. The roller 15 is serrated and driven by a reversible negative drive 10 motor 18, thereby to advance or retract the electrode 2. The drive motor 18 is provided with a normally engaged magnetic brake 19 and a pair of oppositely wound series field windings 20, 21. The magnetic brake 19 is arranged to be disengaged upon energization of the motor 18 by a 15 brake coil 22 connected in series circuit relation in the motor circuit. The series field windings 20 and 21 are arranged to be alternatively connected to the source of control power 9 through the switch 7 and a current regulator 23. The 20 regulator 23 comprises a current responsive actuating winding 24, a pair of normally closed contacts 25 and a pair of normally opened contacts 26. The winding 24 is connected in series 25 circuit relation in the arc circuit of the electrodes 1 and 2. The contacts 25 and 26 are controlled by bridging contact 27. The motor 18, when energized through the series field winding 21, is 30 arranged to drive the electrode 2 in a forward direction toward the electrode 1. The motor field winding 20, when energized, causes the motor 18 to operate in the opposite direction, thereby to retract the electrode 2. The field winding 20 is energized through the contacts 26 only when the 35 current through the arc, and thus through the regulator winding 24, exceeds a predetermined maximum value.

The positive electrode 1 is arranged for continuous rotation and forward feed alternatively 40 at one or the other of two selectable speeds. For this purpose the electrode 1 is mounted in a rotatable head 28 which is journaled in a fixed support 29. The head 28 comprises a hollow sleeve 30 within which the electrode 1 is 45 slidable loosely. The sleeve 30 carries at one end a gear bracket 31. In the gear bracket 31 the electrode 1 is supported between a guide roller 32 and a serrated or toothed driving roller 33. The electrode 1 is further guided and also supplied with 50 current by a pair of spring-pressed electric conducting sliders 34 and 35. Upon the shaft of the driving roller 33 there is mounted a driving pinion 36. The pinion 36 meshes with a worm gear 37 journaled at 38 in the rotatable head bracket 31. The shaft of the worm gear 37 car-

ries at its opposite end a planetary spur gear 39 which meshes with a sun gear 40 journaled in the frame 29 and rotatable with respect to the electrode head 28. Specifically the sun gear 40 is attached to a hollow sleeve 41 which is journaled in the frame 29. On the sleeve 41 adjacent to the sun gear 40 there is mounted a spur gear 42. The hollow sleeve 30 forming part of the rotatable head 28 is rotatably journaled within the sleeve 41. At the end of the sleeve 30 remote from the gear bracket 31 there is mounted a spur gear 43 fixed to the sleeve 30 by a set-screw 44. The spur gear 43 is of slightly greater diameter than the spur gear 42. Finally the gears 42 and 43 are simultaneously and continuously driven by a pair of pinions 45 and 46. The pinions 45 and 46 are journaled in the frame 29 and connected, as by a shaft 47 (indicated schematically), to a driving motor 48. The pinion 46 is slightly smaller than the pinion 45, so that the spur gear 42 is driven at a greater speed than the gear 43. It will of course be appreciated that, if desired, the gear 42 may be driven slightly slower than the gear 43, it being only necessary that the gears 42 and 43 be driven at unequal speed. It may be noted however that if the speed relationship is reversed from that shown it is also necessary to reverse the direction of rotation of the motor 48 so that the electrode 1 will advance.

It will be observed that, in the operation of the positive electrode driving mechanism, the spur gear 43, driven by the motor 48 and attached to the electrode head 28, rotates the electrode head about its own axis, thereby continuously to rotate the electrode 1. If now the spur gear 42 were not driven, but were allowed to rotate idly upon the sleeve 30, it would be carried around by the supporting head 28 and the gears 36, 37 and 39 at the same speed as the head, so that the gears 37 and 39 would not rotate upon their own axis and therefore would not drive the electrode 1 longitudinally. However, the spur gear 42 is positively driven by the pinion 45 at a speed slightly greater than the speed of the head 28 itself. Thus the planetary gear 39 is caused to roll slowly around the sun gear 40, thereby to rotate the worm gear 37 on its own axis and continuously to drive the positive electrode 1 forward as it rotates.

As will be more fully explained hereinafter, the crater at the end of the positive electrode 1 is maintained in a predetermined desired position by providing two selectable driving speeds for the positive head mechanism, in conjunction with a control system responsive to crater position. During normal arcing operation the positive driving motor 48 is connected to the low voltage source of control power 8 through the cut-out switch 7. The motor 48 is provided with a shunt field winding 49. For control of the speed of the motor 48 there is connected in series with the motor armature a variable resistor 50 which is arranged to be shunted by a thermally responsive switch 51. The switch 51 is closed when cold and opens its contacts when hot to insert the resistor 50 in the motor circuit.

The thermally responsive switch 51, and thus the speed of the motor 48, is controlled in accordance with the position of the crater in the end of the positive electrode 1. This control may conveniently be effected by any well known optical system such as that described in U. S. Patent 1,590,543 issued on June 29, 1926, to Martin L. Patterson. Briefly such a system com-

prises an optical arrangement for reflecting the image of the positive crater directly upon the thermal responsive switch member 51 when the crater is in the desired position. In this position of the crater the switch 51 is held open and the motor 48 operates at its low speed. If however the crater burns back farther than desired the image of the crater moves off of the thermal responsive switch member 51. The switch 51 closes its contacts and the speed of the motor 48 is increased, thereby to drive the electrode 1 forward at a greater speed.

With the foregoing description of the various elements of my feed control system, the operation of the system as a whole will now be readily understood from the following brief description.

Let it be assumed that the electrodes are separated as illustrated, and that the cut-out switch 7 is closed. With the cut-out switch 7 closed, energizing circuits are completed for the driving motors 18 and 48, the circuit for the negative drive motor 18 passing through the bridging contact 27 of the regulating relay 23. In parallel circuit relation with the motors there is also completed an energization circuit for the actuating winding 6 of the line contactor 4. Accordingly, therefore, as soon as the switch 7 is closed the driving motors 18 and 48 are placed in operation and the line contactor 4 is picked up to apply arcing voltage to the electrodes.

Since no arc yet exists, the regulator contacts 25 are closed and the negative driving motor drives the electrode 2 forward into engagement with the electrode 1. The positive electrode 1 is simultaneously being driven forward at its maximum speed because the thermal responsive switch member 51 is cold and the resistor 50 shunted. As soon as the electrodes come into contact an arc is struck. The high current through this short arc picks up the regulating relay 23, thereby to close the contacts 26 and to withdraw the electrode 2 by reverse operation of the motor 18. With arcing taking place, the crater at the end of the positive electrode 1 is maintained in a predetermined desired position by operation of the thermal responsive member 51 and the motor 48, and the negative electrode 5 is advanced or retracted as required in order to maintain the arc current substantially constant.

While I have described only a preferred embodiment of my invention by way of illustration, many modifications will occur to those skilled in the art, and I therefore wish to have it understood that I intend in the appended claims to cover all such modifications as fall within the true spirit and scope of my invention.

What I claim as new and desire to secure by Letters Patent of the United States is:

1. In an arc lamp including a pair of arcing electrodes, electrode feed control means for continuously rotating and advancing at least one of said electrodes comprising, a rotatable electrode holder, a concentric sun gear rotatable with respect to said holder, a planetary gear journaled in said holder in meshing engagement with said sun gear, and means for continuously and positively driving said holder and said sun gear at unequal speeds.

2. In an arc lamp including a pair of arcing electrodes, electrode feed control means for continuously rotating and advancing at least one of said electrodes comprising, a rotatable electrode holder, a concentric sun gear rotatable with respect to said holder, a planetary gear journaled in said holder in meshing engagement with said

sun gear, means actuated by rotation of said planetary gear about its own axis for advancing said electrode, and means for continuously and positively driving said holder and said sun gear at unequal speeds.

ROBERT E. SHEAHAN.
